UNITED STATES PATENT OFFICE.

IRVING HUDSON, OF WILKES-BAREE, PENNSYLVANIA.

WINDOW-SCREEN VENTILATOR.

Application filed December 5, 1925. Serial No. 73,498.

To all whom it may concern:

Be it known that I, IRVING HUDSON, a citizen of the United States, residing at Wilkes-Barre, in the county of Luzerne and State 5 of Pennsylvania, have invented certain new and useful Improvements in Window-Screen Ventilators, of which the following is a specification, reference being had to the accompanying drawings.

10 This invention relates to window screen ventilators and it is an object of the invention to provide a device of this kind which, when in applied position, offers no hindrance or obstruction to the desired sliding movement of the window sash and which is constructed in a manner to permit it to be adjusted to be properly applied to window frames of various widths.

15 Another object of the invention is to provide a device of this kind constructed in a manner whereby it may also be employed to properly diffuse within the room the desired disinfectant or fumigant or to moisten the air passing through the device.

20 An additional object of the invention is to provide a device of this kind with means whereby it may be effectively maintained in applied or working position and wherein such retaining means is particularly adapted 25 for coaction with the parting strips of the window frame.

The invention consists in the details of construction and in the combination and arrangement of the several parts of my improved window screen ventilator whereby certain important advantages are attained and the device rendered simpler, less expensive and otherwise more convenient and advantageous for use, as will be hereinafter 30 more fully set forth.

The novel features of my invention will hereinafter be definitely claimed.

In order that my invention may be the better understood, I will now proceed to describe the same with reference to the accompanying drawings, wherein:—

Figure 1 is a view in outside elevation of a window screen ventilator constructed in accordance with an embodiment of my invention and in applied position;

Figure 2 is a view in perspective of one of the sections of the improved device as herein disclosed;

Figure 3 is a view in perspective of the second section of the device as herein employed;

Figure 4 is an enlarged vertical sectional view taken substantially on the line 4—4 of Figure 1;

Figure 5 is a view in top plan of the device in applied position, portions of the window frame being in section.

My improved window screen ventilator, as herein disclosed, comprises two sections A and B of substantially duplicate construction except that one of the sections, as A, is made in a manner to be readily telescoped within the section B.

Each of the sections A and B comprises an outer vertical wall 1 having its major portion cut out, as at 2, and over which is disposed the screen fabric 3 of desired mesh. This fabric 3 may be held in applied position in any desired manner, but as is particularly illustrated in Figure 4 the marginal portions of the fabric are clamped between the reverted flanges 4 disposed inwardly of the wall 1 and defining the cut out portion or opening 2.

Extending inwardly and upwardly from the lower margin of the wall 1 on a predetermined curvature is the inner wall 5, the walls 1 and 5 being preferably formed from a single sheet of material. The outer end of each of the sections A and B is closed by an end plate 6 soldered or otherwise maintained in desired assembled relation.

The outer end of each of the sections A and B is continued by an outstanding flange 7 which is adapted to fit snugly along the inner face of an outer parting strip 8 comprised in the window frame structure F, the outer margin of said frame being provided with a lip 9 which is adapted to be engaged between the parting strip 8 and the adjacent window jamb 10.

Each of the sections A and B has the upper marginal portions of its walls 1 and 5 turned over to provide therealong the tubes or barrels 11 and 12. It is to be noted that the tube or barrel 11 carried by the wall 1 of each of the sections is inwardly disposed while the tube or barrel 12 carried by the wall 5 of each of the sections is outwardly disposed. This arrangement is such so that these tubes or barrels of one of the sections, as A, may be readily received within the corresponding barrels of the second section B and to facilitate this interengagement, the lower portion of the barrel 11 carried by the section B is open to provide a slot 14 while the lower portion of the tube or barrel 12 of

the section A is provided therealong with a slot 15.

In practice, the sections A and B are adapted to be telescopically connected so that they may be relatively adjusted or moved in order to effect the proper fitting of the device within the lower portion of window frames of varying widths. When in applied position, the walls 1 are outwardly disposed with respect to the frame F and the flanges 7 overlie the inner faces of the outer parting strips 8 as hereinbefore referred to, the curvature of the wall 5 resulting in the assembled device being top-heavy at its upper part with a tendency to roll inwardly of the frame. This provides what may be termed gravitational means for maintaining the assembled device in desired position within the window frame. However, by forcing the lips 9 of the flanges 7 between the parting strips 8 and the jambs 10, the device is effectively maintained in place. However, should it be preferred, tacks or the like may be employed in connection with each of the flanges to provide a more positive attachment and for this purpose the upper and lower portions of each of the flanges 7 are provided with the openings 16.

When the device is applied, as is particularly illustrated in Figure 5, it will be readily observed that it offers no hindrance or obstruction to the desired raising or lowering of the lower sash S and also it will be understood that this sash S may be employed to control the admission of air through the screen fabrics 3.

The lower marginal portion of the wall 1 of each of the sections has produced therealong the openings 17 to provide drainage for any water which may be collected within the device and to avoid corrosion it is preferred that the various walls of the sections and the screen fabric be formed of non-rust material.

The lower portion of the wall 5 of each of the sections A and B is adapted to have rested thereon a pan P of desired capacity and in which may be placed water when it is desired to moisten the air as it enters the room or a suitable disinfectant or fumigant may be used.

To further facilitate the positioning of the device within the window frame, the lower portions of the flanges 7 are continued by the depending extension lips 18 which overlie the outer face of the window sill W. These lips 18 are particularly effective in initially positioning the device in place.

It is to be noted that the walls 5 of the sections extend above the openings in the walls 1. This assures the air passing within the room in an upward course.

From the foregoing description it is

thought to be obvious that a window screen ventilator constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A window screen ventilator comprising two members one adapted to telescope within the other, each of said members comprising an outer wall having a relatively large opening, a screen fabric carried by said wall and disposed over the opening, an inner wall extending upwardly from the lower margin of the outer wall on a predetermined curvature, a plate connecting the outer ends of said outer and inner walls, the outer wall extending beyond said plate for contact with the parting strip of a window frame when the device is in applied position, the upper marginal portions of the outer and inner walls of each of the sections being provided therealong with inwardly disposed barrels, the barrels of one section sliding within the barrels of the second section, a barrel of each of the sections being slotted to permit requisite relative sliding movement of the sections.

2. A window screen ventilator comprising two members one adapted to telescope within the other, each of said members comprising an outer wall having a relatively large opening, a screen fabric carried by said wall and disposed over the opening, an inner wall extending upwardly from the lower margin of the outer wall on a predetermined curvature, a plate connecting the outer ends of said outer and inner walls, the outer wall extending beyond said plate for contact with the parting strip of a window frame when the device is in applied position, the upper marginal portions of the outer and inner walls of each of the sections being provided therealong with inwardly disposed barrels, the barrels of one section sliding within the barrels of the second section, a barrel of each of the sections being slotted to permit requisite relative sliding movement of the sections, the portion of the plate of each section extending beyond the outer plate having its lower end continued by a lip adapted for contact with the outer face of a window sill when the device is in applied position.

In testimony whereof I hereunto affix my signature.

IRVING HUDSON.
